CLAIM

The ornamental design for a mobile phone display screen with graphical user interface, as shown and described.

DESCRIPTION

FIG. 1 is a front view of the first image in a sequence of a mobile phone display screen or portion thereof with graphical user interface showing our new design.

FIG. 2 is a front view of the second image in a sequence thereof.

FIG. 3 is a front view of the third image in a sequence thereof.

FIG. 4 is a front view of the fourth image in a sequence thereof.

FIG. 5 is a front view of the fifth image in a sequence thereof; and,

FIG. 6 is a front view of the sixth image in a sequence thereof.

The appearance of the transitional image sequentially transitions between FIGS. 1-6. The process or period in which one image transitions to another image forms no part of the claimed design.

FIG. 1 shows the mobile phone environment of the claimed design. FIGS. 2-6 shows only the display screen portion of the mobile phone.

The broken lines showing of the edges of the display screen of a mobile phone in FIGS. 1-6 and the mobile phone environment in FIG. 1 form no part of the claimed design.

1 Claim, 6 Drawing Sheets
